TANK FOR A PORTABLE SPRAYER

Fernand Berthoud, Belleville-sur-Saone, France, assignor
to Berthoud, Belleville-sur-Saone, Rhone, France

Filed May 30, 1974, Ser. No. 474,401

Term of patent 14 years

Int. Cl. D23—01

U.S. Cl. D23—2

Fig. 5

Fig. 4

Fig. 6

Fig. 2

Fig. 1

Fig. 3

FIG. 1 is a top view of a tank for a portable sprayer showing my new design.

FIG. 2 is a front view thereof.

FIG. 3 is a rear view thereof.

FIG. 4 is a bottom view thereof.

FIG. 5 is a side view thereof.
FIG. 6 is a view taken the side opposite to that shown in FIG. 5.

I claim:

The ornamental design for a tank for a portable sprayer, as shown.
